WINDOW CONSTRUCTION

Harold M. Woelfel, Montreal, Quebec, Canada,
assignor to The Robert Mitchell Co. Limited,
Montreal, Quebec, Canada

Application September 28, 1938, Serial No. 232,173

7 Claims. (Cl. 189—64)

This invention relates to an improved window assembly for use in air conditioned railway cars and in other relations.

One object of the invention is to provide simple and easily applied sealing and shock absorbing means for detachably securing a window sash in fixed position within a window frame. This object is accomplished by fitting the sash between resilient inner and outer sealing members made of rubber or other suitable shock absorbing material, said sealing members engaging the top, bottom and side rails of the sash with sufficient pressure to prevent rattling of the sash, in addition to providing a tight joint between the sash rails and adjacent portions of the window frame. The sealing member at one side of the sash is fixedly secured to the window frame but the sealing member at the opposite side of the sash is adjustable in the window frame to vary its effective pressure against the sash rails.

Another object of the invention is to provide a metal window sash and frame assembly in which heat conducting members, insulated from the metal window frame, are employed for conducting heat from the interior of the enclosure in which the window assembly is installed to the metal rails of the sash to prevent "frosting" thereof in cold weather. To this end the window is equipped with a metal sill which contacts the bottom rail of the sash and is insulated from the metal of the window frame by suitable thermal insulating means, said sill being preferably made of aluminum of sufficient thickness to serve as a good heat conductor. The invention also contemplates conduction of heat to the side rails of the sash through metal curtain guides or other metal elements which constitute part of the inside trim of the window and are insulated from the metal of the window framing.

Other objects, advantages and characteristic features of the invention will be more readily understood from the following detailed description taken in connection with the accompanying drawings, in which—

Fig. 1 is a vertical sectional view of a portion of the wall structure of a railway car equipped with my improved window assembly.

Fig. 2 is a transverse sectional view along the line 2—2 of Fig. 1.

Fig. 3 is an enlarged sectional view of the sill or jamb construction appearing in Fig. 1.

Referring more particularly to the drawings, 5 5 designates a double glazed insulating sash mounted in the window frame 6 of a steel railway car 7, said frame being bounded at the sides

by sheet metal window posts 8 extending from the metal sill rail 9 to the metal head rail or lintel 10. Sash 5 is held in place between outer and inner sealing and shock absorbing members respectively indicated at 11 and 12. These sealing and shock absorbing members are made of rubber or other resilient shock absorbing material in the form of open rectangular frames presenting top, bottom and side portions engaging the corresponding rails of the sash. Member 11 is cemented in place within an inwardly facing rectangular channel 13 provided at the outer side of the metal window frame and constitutes a fixed abutment for the outer sides of the sash rails. The inner sealing member 12 is secured in the channel 14 of a rectangular holder 15 which is a snug sliding fit in the window frame 6.

The pressure with which the rails of the sash are gripped between the sealing and shock absorbing members 11 and 12 may be regulated through the agency of pressure applying screws 16. The screws 16 engaging the top portion of the holder 15 are carried by a downwardly directed flange 17 provided at the inner edge of the metal head rail or lintel 10. The screws 16 engaging the vertical sides of the holder 15 are carried by suitable brackets 18 fastened to the inner sides of the window posts 8. The remaining screws 16 which engage the bottom portion of the holder 15 are carried by a steel bar 19 located directly above the metal sill rail 9.

After the window sash has been fitted in place between the sealing and shock absorbing members 11 and 12 the screws 16 are turned to force the holder 15 outwardly until the desired pressure is exerted against the inner sides of the sash rails by the movable sealing and cushioning member 12. This pressure may therefore be conveniently regulated to ensure a tight joint between the sash rails and the adjacent portions of the window frame. In addition to their sealing and shock absorbing functions the members 11 and 12 also serve to prevent rattling of the sash.

The sash shown in the present instance is made in accordance with the invention disclosed in my prior U. S. Patent No. 2,128,370 granted Aug. 30, 1938. It comprises a preformed multi-pane glazing unit 22 mounted in a suitable sash frame 23. Unit 22 comprises transparent indoor and outdoor panes 24 and 25 spaced apart by plastic sealing means 26 interposed between the marginal edges which are also held together by a thin closely fitting U-shaped metal frame 27. The sash frame 23 in which this glazing unit is se-

cured comprises inner and outer frame sections substantially L-shaped in cross section. These frame sections are fitted together so that their flanges 28 form the side walls of a channel in which the marginal portions of the glazing unit is sealed by a suitable caulking compound. The bottom of the glazing receiving channel is formed by flanges 29 disposed in overlapping relation and held out of direct contact with each other by an interposed layer 30 of fibrous or other suitable insulating material of low thermal conductivity. The flanges 29 are secured together by screws 31 passing through the interposed insulating material 30.

One of the difficulties experienced in connection with metal window sashes, especially when installed in the window frames of metal railway cars, is the occurrence of what is known as "frosting" or "sweating" of the frame. This is due to the transmission of cold from the outside to the inside through the metal of the sash itself or through the metal window frame or other metal parts in contact with the sash. In the present instance the transference of cold from the outside to the inside through the metal of the sash itself is prevented by the insulating effect of the rubber sealing and shock absorbing strips 11 and 12 and by constructing the sash frame so that the inner and outer frame sections are held out of direct contact with each other by insulating material.

In addition to these safeguards the present invention also provides for conduction of heat from the interior of the car to the inner surfaces of the sash rails to assist in preventing "frosting" thereof. To this end the window assembly is provided with a metal sill 33 made of aluminum or some other metal which is a good conductor of heat. This sill is mounted on the metal sill rail 9 but is insulated therefrom by interposed thermal insulation 34. This insulation may be composed of wood or other suitable material and is here shown as a laminated body consisting of a plurality of superposed plies cemented or otherwise secured together. It is fastened to the metal sill rail 9 by screws 35 and supports the metal sill 33 which is secured thereto by short screws 36. Since frosting of the heads of the screws 36 is undesirable it is important that these screws should not touch the screws 35 nor the metal head rail 9. Sill 33 is shown mounted on the insulation 34 so that its inner edge 33a is butted against the bottom rail of the window sash in direct contact therewith. The opposite edge of the sill is bent downwardly and inwardly to provide the flange 33b which rests on insulating material 37 which forms part of the inside trim or finish of the car. In the winter time a considerable amount of heat is conducted from the interior of the car to the metal sash frame through the metal sill 33 and materially assists in preventing "frosting" of the inside rail surfaces of the sashes. The cold transmitted from the outside to the inside of the car through the metal sash rail 9 does not affect the heat transferring efficiency of the sill 33 since these parts are completely insulated from each other by the interposed insulating material 34 and 37.

The metal curtain guides 39 applied to the opposing surfaces of the window posts 8 may also be utilized to serve as heat conductors through which heat is conducted from the inside of the car to the side rails of the metal sash. When the curtain guides are used for this purpose they

are insulated from the window posts 8 as indicated at 40 and 41.

As shown to advantage in Fig. 1, the outer portions of the adjusting screws 16 engaging the lower rail of the sash may be fitted in suitable openings 34a provided in the laminated insulating body 34. The openings 34a extend entirely through the insulation 34 and are provided with enlarged inner portions 34b in which the heads of the screws 16 are accommodated. The portions 34b of openings 34a are large enough to permit insertion of a screw driver for turning the heads of the screws.

Having thus described my invention, what I claim is:

1. A window construction comprising a window frame, a rubber cushioning and sealing member fitted in an inwardly facing channel surrounding the window opening of the frame at the outer side of said frame, a sash frame arranged in the window frame with the outer sides of the sash rails butted against said member, a second rubber cushioning and sealing member arranged in said window frame for engagement with the inner side of the rails of the sash frame, a channel frame in which said second sealing and cushioning member is secured, said channel frame being slidably arranged within the window frame at the inner side of the sash frame and being slidably supported in said window frame, bracket members arranged within and secured to said window frame at the inner side of said channel frame and adjusting screws threaded through said bracket members into pressure applying engagement with the inner side of said slidably mounted channel frame.

2. A window construction as set forth in claim 1 including a sill member secured to the sill rail of the window frame and covering the lower portion of said slidably mounted channel frame.

3. A window construction as set forth in claim 1 including curtain guides secured to the side members of the window frame and covering the side portions of the slidably mounted channel frame.

4. A window construction as set forth in claim 1 including a sill member secured to the sill rail of the window frame and covering the bottom portion of the slidably mounted channel frame and curtain guides secured to the side members of the window frame and covering the side portions of the channel frame.

5. A window construction as set forth in claim 1 in which the top, bottom and side portions of the slidably mounted channel frame are covered by stationary covering members secured to the top, bottom and side members of the window frame.

6. A window construction comprising a metal window frame provided at the outer side with an inwardly facing channel located within a window opening defined by the top, bottom and side members of said frame, a non-metallic cushioning and sealing member secured in said channel, a metal sash frame arranged in the window frame out of metal to metal contact therewith and with the outer sides of the rails of the sash frame butted against said cushioning and sealing member, a second non-metallic cushioning and sealing member butted against the inner sides of the sash rails, a channel frame in which said second sealing and shock absorbing member is secured, said channel frame being slidably arranged within the window opening of the window frame at the inner side of the sash frame, a heat conducting

metal sill member supported on but insulated from the sill rail of the metal window frame, said sill member covering the bottom portion of the slidably mounted channel frame and having its outer marginal portion disposed in metal to metal contact with the inner side of the bottom rail of the sash frame.

7. A window construction comprising a metal window frame, a metal sash mounted in said frame between inner and outer sealing and shock absorbing members made of resilient non-metallic material, said sealing members engaging the top, bottom and side rails of the sash and being tightly pressed thereagainst, said sash being mounted between said sealing members so that there is no direct metal to metal contact between

5 the sash and the window frame, a holding frame in which the inner sealing and shock absorbing member is mounted, said holding frame being slidably arranged in the window frame, means for applying pressure to said holding frame to force the inner sealing and shock absorbing member into pressure contact with the sash and a metal sill member mounted on but insulated from the bottom sill rail of the window frame, said sill member being in direct metal to metal contact with the bottom rail of the sash and serving as a heat conductor for conducting heat to said rail from the interior of the enclosure in which the window construction is installed.
